Fig. 3

Fig. 4

To all whom it may concern:

Be it known, that we, John A. Frazier and Edmond A. May, citizens of the United States of America, residing at Dallas, in the county of Dallas and State of Texas, have invented a new, original, and ornamental Design for a Loud-Speaker, of which the following is a specification, reference being had to the accompanying drawing, forming a part thereof, wherein:

Figure 1 is a front perspective view of a loud-speaker showing our new design,

Figure 2 is a side elevation of the loud-speaker,

Figure 3 is a front elevation of the loud-speaker, and,

Figure 4 is a top plan view of the loud-speaker,

The dominant characteristics of the design are the divergently tapered top, bottom and sides, from rear to front of the outer portion speaker, and of the central portion thereof, together with the rigid spacers uniformly positioned between the sides and between the top and inner and bottom and inner walls.

We claim:

The ornamental design for a loud-speaker, substantially as shown and described.
